CLAIM

The ornamental design for a weightlifting system, as shown.

DESCRIPTION

FIG. 1 is a front upper perspective view of a weightlifting system in an environment.

FIG. 2 is a front upper perspective view of the weightlifting system of FIG. 1.

FIG. 3 is a rear lower perspective view of the weightlifting system of FIG. 1.

FIG. 4 is a front view of the weightlifting system of FIG. 1.

FIG. 5 is a rear view of the weightlifting system of FIG. 1.

FIG. 6 is a right side view of the weightlifting system of FIG. 1.

FIG. 7 is a left side view of the weightlifting system of FIG. 1.

FIG. 8 is a top view of the weightlifting system of FIG. 1.

FIG. 9 is a bottom view of the weightlifting system of FIG. 1.

FIG. 10 is a front upper perspective view of an upper portion of the weightlifting system of FIG. 1.

FIG. 11 is a front lower perspective view of the upper portion of the weightlifting system of FIG. 10.

FIG. 12 is a front view of the upper portion of the weightlifting system of FIG. 10.

FIG. 13 is a rear view of the upper portion of the weightlifting system of FIG. 10.

FIG. 14 is a right side view of the upper portion of the weightlifting system of FIG. 10.

FIG. 15 is a left side view of the upper portion of the weightlifting system of FIG. 10.

FIG. 16 is a top view of the upper portion of the weightlifting system of FIG. 10.

FIG. 17 is a bottom view of the upper portion of the weightlifting system of FIG. 10.

FIG. 18 is a front upper perspective view of a lower portion of the weightlifting system of FIG. 1.

FIG. 19 is a front lower perspective view of the lower portion of the weightlifting system of FIG. 10.

FIG. 20 is a front view of the lower portion of the weightlifting system of FIG. 10.

FIG. 21 is a rear view of the lower portion of the weightlifting system of FIG. 10.

FIG. 22 is a right side view of the lower portion of the weightlifting system of FIG. 10.

FIG. 23 is a left side view of the lower portion of the weightlifting system of FIG. 10.

FIG. 24 is a top view of the lower portion of the weightlifting system of FIG. 10; and,

FIG. 25 is a bottom view of the lower portion of the weightlifting system of FIG. 10.

In the figures, the dashed lines indicate environmental or other features that form no part of the claimed invention.
